UNITED STATES PATENT OFFICE.

JULIUS F. GOETZ, OF HARTFORD, WISCONSIN.

LIGHTNING-ROD.

1,153,617.

Specification of Letters Patent. Patented Sept. 14, 1915.

Application filed December 14, 1911. Serial No. 665,863.

To all whom it may concern:

Be it known that I, JULIUS F. GOETZ, a citizen of the United States, and resident of Hartford, in the county of Washington and State of Wisconsin, have invented new and useful Improvements in Lightning-Rods, of which the following is a description, reference being had to the accompanying drawings, which are a part of this specification.

10 This invention has for its object to provide a lightning rod which will be flexible so as to be readily bent around corners and edges of the building and which at the same time will be less expensive than cable constructions at present in use.

15 The invention further designs to provide a lightning rod comprising a flat strip of flexible material which is coiled helically to form a hollow self sustaining core upon which the wires forming the surface of the rod are wound and supported.

With the above and other objects in view the invention consists in the lightning rod herein claimed and all equivalents.

20 Referring to the accompanying drawings in which like characters of reference indicate the same parts in different views: Figure 1 is a perspective view of a fragment of lightning rod constructed in accordance with 25 this invention and shown on a large scale for sake of clearness of illustration; and, Fig. 2 is a transverse sectional view thereof.

In these drawings 10 indicates the core which is formed from a flat strip of self-sustaining flexible material, preferably of sheet metal, such as copper, said strip being coiled in the form of a helix, said helix forming a hollow core upon which the wires forming the surface of the rod are wound and supported. The strip of material being initially flat when it is coiled the convolutions of the coils will form bearing surfaces for the wires as the convolutions of the coils are of the same diameter the successive coils 40 will form a longitudinally extending bearing surface, portions of which are spaced apart at each convolution of the coil.

The pitch on which the ribbon is coiled is 45 preferably so great as to leave considerable space between the convolutions thereof, equal to or greater than the width of the ribbon but the distance between the convolutions may be varied without departing from the invention. Around the core 10 are wound a series of wires 11 which are ar-

ranged side by side so as to complete a cylindrical formation and these wires are coiled in the direction opposite to the direction of turning of the ribbon forming the core but preferably at a pitch greater than the pitch of the convolutions of the ribbon, so that each strand of wire will cross the successive convolutions of the ribbon 10 and be held in place thereby. The resiliency of the wires is sufficient to cause them to bridge the gap between the successive convolutions of the core without disturbing the uniformity in the appearance of the cylindrical hollow cable construction.

The invention possesses the advantage over solid cable constructions, in which the entire body is made up of strands of wire, of being lighter to handle and less expensive to manufacture, while possessing the same efficiency because of the fact that the effective conductivity of a lightning rod is determined by its external surface only.

The light sheet metal core is flexible to a sufficient extent to enable the cable to be bent as desired to avoid projections of the building and to enable it to be placed wherever desired without the formation of angle joints.

What I claim as new and desire to secure by Letters Patent is:

1. A lightning conductor comprising a hollow self-sustaining wire-supporting core formed from a flat strip of flexible material, and an outer surface, inclosing said core, comprising a plurality of wires wound upon the core to form a conductor.

2. A lightning conductor comprising a hollow self-sustaining wire-supporting core formed from a strip of flexible material helically coiled, and an outer surface, inclosing said core, comprising a plurality of helically coiled wires wound upon the core to form a conductor tube.

3. A lightning conductor comprising a hollow self-sustaining wire-supporting core formed from a flat strip of flexible electrical-conducting material helically coiled, and an outer surface, inclosing said core, comprising a plurality of helically coiled wires wound around upon the bearing surfaces formed by the convolutions of the helical coil of the core to form a conductor tube.

4. A lightning conductor comprising a hollow self-sustaining wire-supporting core formed from a flat flexible metal strip heli-

cally coiled, and an outer surface, inclosing said core, comprising a plurality of helically coiled wires wound around upon the bearing surfaces formed by the convolutions of the 5 helical coils of the core and across the gaps between the alternate convolutions of the coil to form a conductor tube.

In testimony whereof, I affix my signature, in presence of two witnesses.

JULIUS F. GOETZ.
